HOLDER FOR A HANDBAG OR SIMILAR ARTICLE

Harry Kore, Jr., 500 N. 11th St., Reading, Pa.

Filed Nov. 10, 1961, Ser. No. 67,472

Term of patent 14 years

(Cl. D33—3)

The broken lines shown on the drawing are for illustrative purposes only.

I claim:

The ornamental design for a holder for a handbag or similar article, as shown and described.
